CLAIM

I claim the ornamental design for a roll towel dispenser roller, as shown and described.

DESCRIPTION

This application is related to U.S. Des. patent application Ser. No. 29/647,869, filed on May 16, 2018, entitled "Housing for a Roll Towel Dispenser," which is incorporated herein by reference in its entirety.

FIG. 1 is a top, front, right perspective view of a roll towel dispenser roller showing my new design within its environment of a roll towel dispenser with a front cover of the housing removed

FIG. 2 is a front, right, perspective view of the claimed design of FIG. 1;

FIG. 3 is a front side view of the claimed design of FIG. 1;

FIG. 4 is a rear side view of the claimed design of FIG. 1;

FIG. 5 is a left side view of the claimed design of FIG. 1;

FIG. 6 is a right side view of the claimed design of FIG. 1;

FIG. 7 is a top view of the claimed design of FIG. 1; and,

FIG. 8 is a bottom view of the claimed design of FIG. 1.

Broken lines are used to illustrate environmental subject matter that form no part of the claimed design. None of the broken lines form any part of the claimed design.
